UNITED STATES PATENT OFFICE.

EDDIE A. PETERSON, OF CASPER, WYOMING.

TIE PLATE.

Application filed December 8, 1921. Serial No. 520,967.

To all whom it may concern:

Be it known that I, EDDIE A. PETERSON, a citizen of the United States, residing at Casper, in the county of Natrona and State 5 of Wyoming, have invented certain new and useful Improvements in Tie Plates, of which the following is a specification.

This invention relates to improvements in railroad tie plates.

10 The primary object of this invention is the provision of a tie plate embodying a novel arrangement of tie engaging ribs, and having certain openings disposed in cooperation with said ribs for the most effective 15 reception of attaching spikes.

A further object of the invention is the provision of an improved tie plate which may be used as a splice connection for attaching the ends of abutting rail sections.

20 Other objects and advantages will be apparent during the course of the following detailed description.

In the accompanying drawing, forming a part of this specification, and wherein similar reference characters designate corresponding parts throughout the several views.

25 Figure 1 is a perspective view of a portion of a wooden tie, having the improved tie plate assembled in position thereon, a 30 rail section being shown in dotted lines to demonstrate the relative position the same will assume when connected.

Figure 2 is a transverse cross sectional view taken on the line 2—2 of Figure 1.

35 Figure 3 is a longitudinal cross sectional view taken on the line 3—3 of Figure 1, and showing the manner in which the plate cooperates with a tie to prevent lateral shifting of the same.

40 Figure 4 is a bottom plan view of the improved tie plate, showing the novel construction thereof.

In the drawings, the letter A designates a tie, which may be of wood or any approved 45 material having the tie plate B mounted thereon to receive a rail C, said tie plate B and rail C having the ordinary spikes D for secure attachment of the tie plate and rail section to the tie.

50 The tie plate B includes the body plate 10, which is greater in length than the transverse dimension of the rail flange, and which feature has been provided in order that a portion of the body plate 10 may

project from each marginal edge of a rail 55 base flange. It is preferred that the inside marginal edge 12 of the body portion 10 be less in thickness than the thickness of the portion of said body 10, upon which the rail base rests, a bevelled upper surface 13 adjacent said marginal edge 12 being provided to facilitate entrance of the tie plate B beneath a rail section C. The advantage in this formation can readily be seen, since thereby the body portion 10 of the tie plate 60 B may be easily forced beneath the base flange of a rail section.

The outside part of the body portion 10 is provided with an overhanging flange 14, preferably formed integral with the body 70 portion 10, and which is provided with the under flat surface 15 adapted for engaging the top surface of one side of a rail base flange. The overhanging flange 14, in fact, forms a pocket like opening 16 for snug 75 reception of one side of a rail base flange, the overhanging flange 14 being so formed as to engage the base flange of a rail section throughout the width of the tie plate B, the forward marginal edge 18 of the overhanging flange 14 extending to contact the web 80 portion of a rail member C.

The bottom surface of the tie plate B is of unusual formation, and is provided with the depending transverse ribs 25 upon the 85 marginal edges of the plate B, and the depending ribs 26 upon the longitudinal marginal edges of the plate B. The intersecting transverse ribs 28 and longitudinal ribs 29 are provided upon the bottom of said tie 90 plate B, which cross each other substantially at right angles, and thus providing a plurality of rectangular or polygonal shaped pockets or depressions 30 extending upwardly from the bottom of the tie plate B, 95 said depressions or pockets 30 being all of substantially the same dimensions. It is preferred that the ribs 28 and 29 be substantially U-shaped in cross section, and whereby the extreme lower surfaces 31 of 100 said ribs are flat, having the sides 32 thereof beveling upward in diverging relation to the bottom surface 31, as is illustrated in Figures 2, 3, and 4 of the drawings. It can thus be seen that the pockets 30 decrease in 105 size from their entrance, the marginal edges of said pockets 30 all converging upwardly. It is likewise preferred that the marginal

depending ribs 25 and 26 have their inside edges beveling upwardly similar to the sides 32 above described.

The tie plate B is preferably provided 5 with spike receiving apertures 20 and 21 disposed transversely through the body portion 10 of said plate, said apertures being so positioned as to effectively retain the plate in conjunction with a rail. It is preferred 10 that these openings 20 and 21 be elongated and disposed in intersecting alignment with the longitudinal ribs 29, substantially as is illustrated in Figure 4 of the drawing. Each of these slots 20 and 21 also includes 15 a straight spike engaging surface 35, which is, of course, disposed transversely of the plate 10. For the opening 21 which is merely disposed through the thickness of the body portion 10, it is preferred that this 20 straight portion 35 directly intersect through a transverse rib 28 for reinforcing purposes. In view of the fact that the opening 20 is partially disposed through the overhanging flange portion 14, and at the juncture there- 25 of with the body portion 10, the straight portion 35 of said opening 20 has ample re- 30inforcing surface independent of extension of the same through a transverse rib 28. However, it is a feature of this invention 35 that the apertures 20 and 21 are directly disposed at a point of intersection of a trans- 40verse rib 28 with a longitudinal rib 29, so that the attaching spikes D may have sufficient reinforcement insofar as the tie plate 45 is concerned. In view of the fact that the longitudinal ribs 29 are disposed at right angles to the run of a rail C, and since the openings 20 and 21 are directly disposed through said ribs 29, it can readily be under- 50stood that during attachment of the rail upon a tie plate, the said tie plate will not be liable to become chipped or split incident to the driving of the spike D therein, since should the workman miss the spike D during 55 driving of the same, the driving tool will hit

the plate just above a longitudinal rib 29, as can be understood. In this manner, the plate B is constructed in the most favorable manner for the effective reception of rails.

The advantage of providing the ribs 25, 50 26, 28 and 29 is apparent, since when the tie plate B is disposed upon its tie A, the fibers of said tie A will swell upwardly into the pockets 30. In lieu of the ordinary wood tie A, a composition tie may be provided 55 with certain intersecting channels for the reception of the depending ribs of the tie plate B. However, it is obvious that when the rails C are disposed in proper manner upon the tie plates B, and after the rolling stock has settled the tie plates B, the fibers will swell upwardly into the pockets 30. In this manner, the tie plates B will be more 60 securely attached to the tie A, preventing any lateral creeping thereof, such as is ordi- 65narily incident to wheel thrust and other exterior causes. It can readily be seen that it will be almost impossible to shear off the bulging of the tie A which extend into the pockets 30.

From the foregoing, it is apparent that a tie plate has been provided, which will be positioned upon a tie in a more secure relation to seat the rail sections thereon for maintaining a proper railway gauge.

Various changes in the shape, size and arrangement of parts, may be provided, without departing from the spirit of the invention or the scope of the claim.

I claim:

As an article of manufacture, a tie plate for rails embodying a plurality of right angled intersecting longitudinal and trans- 85verse ribs, said plate having slots extending therethrough in direct intersecting alignment with longitudinal ribs thereof, said slots having certain spike engaging surfaces thereon arranged in direct intersecting relation with transverse ribs thereof.

EDDIE A. PETERSON.
